(57) **CLAIM**

The ornamental design for a water-tight container, as shown.

DESCRIPTION

FIG. 1 is a front perspective view of a water-tight container of our design;

FIG. 2 is a top plan view thereof;

FIG. 3 is a front elevational view thereof;

FIG. 4 is a bottom plan view thereof;

FIG. 5 is a right side elevational view thereof;

FIG. 6 is a left side elevational view thereof;

FIG. 7 is a rear elevational view thereof;

FIG. 8 is a front perspective view of a second embodiment of a water-tight container, the second embodiment being identical to the first, save for proportions and the addition of a rear clip;

FIG. 9 is a rear perspective view of FIG. 8; and,

FIG. 10 is a rear perspective view of a third embodiment of a water-tight container, the third embodiment being identical to the first, save for proportions and the addition of a rear clip.
